UNITED STATES PATENT OFFICE.

JAMES L. MURPHY, OF CHICAGO, ILLINOIS.

DESIGN FOR A COLLAR-SUPPORT.

44,319.

Specification for Design.

Patented July 8, 1913.

Application filed February 3, 1913. Serial No. 746,061. Term of patent 7 years.

To all whom it may concern:

Be it known that I, JAMES L. MURPHY, citizen of the United States, residing at Chicago, in the county of Cook and State of Illinois, have invented a new and original and ornamental Design for a Collar-Support, of which the following is a specification, reference being had to the accompanying drawing, forming a part thereof.

The figure is a front elevation of a cellu-loid collar support, showing large perforations on both ends, and in the center of the frame a brace to the rear collar button.

I claim:

The ornamental design for a collar support, as shown.
